UNITED STATES PATENT OFFICE

110,994

DESIGN FOR A COMBINED WASHING MACHINE AND DRIER

Henry W. Altorfer, Peoria, Ill.

Application June 7, 1937, Serial No. 69,717

Term of patent 14 years

To all whom it may concern:

Be it known that I, Henry W. Altorfer, a citizen of the United States, residing at Peoria, in the county of Peoria and State of Illinois, have invented a new, original, and ornamental Design for a Combined Washing Machine and Drier, of which the following is a specification, reference being had to the accompanying drawings, forming part thereof, in which

Fig. 1 is a perspective view of a combined washing machine and drier, showing my new design; Fig. 2 is a similar view of the combined washing machine and drier, as shown when viewed from the side opposite to that shown in Fig. 1.

I claim:

The ornamental design for a combined washing machine and drier, as shown.

HENRY W. ALTORFER.
